UNITED STATES PATENT OFFICE.

THOMAS F. GAYNOR, OF NEW YORK, N. Y.

DESIGN FOR A BADGE.

No. 39,599.

Specification for Design.

Patented Oct. 6, 1908.

Application filed August 28, 1908. Serial No. 450,793. Term of patent 3½ years.

To all whom it may concern:

Be it known that I, THOMAS F. GAYNOR, a citizen of the United States, and a resident of Brooklyn, New York city, in the county of Kings and State of New York, have invented a new, original, and ornamental Design for Badges, of which the following is a specification, reference being had to the accompanying drawings, forming a part thereof.

In the drawings:—Figure 1, is a front ele-

vation of a badge made according to my design, and as applied to a pin form of badge. Fig. 2, is a side elevation of Fig. 1.

I claim:

The ornamental design for a badge, as shown.

THOMAS F. GAYNOR.
